DESIGN FOR A HANDLE FOR DRY SHAVERS

Jacob Schick, Stamford, Conn.

Application November 22, 1935, Serial No. 59,702

Term of patent 3½ years

To all whom it may concern:

Be it known that I, Jacob Schick, a citizen of the United States, residing in Stamford, in the county of Fairfield and State of Connecticut, have invented a new, original, and ornamental Design for a Handle for Dry Shavers, of which the following is a specification, reference being had to the accompanying drawing, forming part thereof,

Figure 1 is a face view, Figure 2 is an edge view and Figure 3 is a back view of a handle for dry shavers, showing my new design.

I claim:

The ornamental design for a handle for dry shavers, as shown.

JACOB SCHICK,
